UNITED STATES PATENT OFFICE

2,616,276

KNITTING MACHINE FOR AND METHOD
OF PLATINGCharles F. Miller, Philadelphia, Pa., assignor to
Jacquard Knitting Machine Co., Inc., Philadelphia, Pa., a corporation of New York

Application July 20, 1949, Serial No. 105,727

6 Claims. (Cl. 66—136)

1

This invention relates to plating in knitting, that is to say, to the production of knit fabrics in which each loop (or each of a number of the loops) is composed of a number of yarns lying one upon another.

Heretofore plating has been done by various placements and handlings of the yarns. The present invention provides a simple method of plating that I prefer. Basically this method involves delivering the yarns to the needle bank side by side as it were, i. e. more or less in a plane, about perpendicular to the needle staves, and then adjacent the needles thrusting the outermost yarn toward the needle staves and to positions at one side or the other of the innermost yarn lengthwise of the needles. With knitting machines employing latch needles, the needle latches can be used to thrust the outer yarns to their positions at the needles.

Preferably I use what I call plating guides to direct the yarns toward the needles, especially when yarn changers are used so that one yarn can be replaced by another or one set of yarns replaced by another set on occasion. The plating guides are located between the yarn feeders and the needles. The desired yarn placements can be obtained more readily by a plating guide than by the movable yarn fingers or feeding fingers of yarn changers.

Further, the invention contemplates the production, when desired, of fabrics having a side or face formed of yarns of different characters, such as different colors or different textures. To this end it employs the plating arrangement referred to above in machines that knit by drawing some of the loops to one side of the fabric and the other loops to the other side of the fabric, for example, in the manner of links-and-links machines. With such arrangements, and without any manipulation other than that mentioned above, and that which causes some loops to be drawn to one side or face of the fabric and other loops to the opposite side or face, a side of the fabric can be made of yarns of different characters placed in various fancy arrangements as desired.

The foregoing and other matters of the invention are illustrated in the accompanying drawings. Fig. 1 is a rather diagrammatic illustration of successive relative positions of two yarns and, say, successive needles of a bank operating, or, say, successive positions of the same needle, while drawing a loop in accordance with the invention. Fig. 2 is a quite diagrammatic plan view of the matter of Fig. 1. Fig. 3 is a side ele-

2

vation of the needle operations of a links-and-links type of knitting machine in accordance with the present invention. Fig. 4 is a vertical section of the principal parts of one side of one form of links-and-links machine, and Fig. 5 illustrates generally one of the known camming arrangements (for one feed only) now used in such machines, and the approximate relation of the yarn guide to the drawing of the loops in knitting machines. Fig. 6 is a perspective view of the plating guide of other figures. Fig. 7 is a plan view showing the relations of the yarn fingers of a yarn changer to such a yarn guide and a circular bank of needles.

Fig. 1 illustrates generally the operations of knitting with plating in accordance with the present invention. As shown, a black yarn 10 and a white yarn 11 are fed to the needles through, say, two yarn guides 12 and 13. In the instance shown, these yarn guides are feeding fingers of a yarn changer, and especially in such cases there may be another or other yarn guides or feeder fingers such as 15, for example, furnished with another or other yarns such as 14. The feeder fingers and other parts of the yarn changer may be mounted on a bracket 16 which in turn is mounted on, say, the cam ring of the machine, while actuators 18 for the fingers and cooperating movable members 19, adjusted by a pattern mechanism (not shown), serve to move the feeder fingers toward and from feeding position so that, say, any one or two of the various yarns can be fed to the needles as desired. Inasmuch as yarn changers are well known and the specific nature of the yarn changer is not material to the invention, the foregoing and the illustration in Fig. 7 is sufficient for the present purposes. It is to be understood, however, that a yarn changer is not a wholly necessary element of the invention; i. e. the yarns can be fed by fixed yarn guides; e. g. two yarns from one or two guides fixed at the positions of 12 and 13 in Figs. 2 and 7.

As before indicated, I prefer to use a plating guide, such as 20, between the yarn guides or fingers and the needle bank (at each feed, if the machine is a multiple feed machine), to assure the yarns approaching the needles in the desired relative positions. This is not wholly necessary however, especially where the yarn guides, e. g. at 12 and 13, are mounted permanently in yarn-feeding positions; it is quite desirable when yarn changers are used however. The plating guide is mounted in a fixed position with respect to the needle bank position; e. g. it may be mounted on

a cam ring of the knitting machine. The plating guide has at least one guide surface (perhaps an eye but usually a notch or edge) on which the yarns pass, and preferably an individual recess for each yarn in action; e. g. a notch 22 for guiding the yarn 11 and a notch 23 for the yarn 10. When a yarn changer is used with a plating guide, its yarn fingers can be so related that when one finger e. g. 13, is taken out of action another finger e. g. 15, can be brought to such a position that its yarn will occupy the same guide surface on the plating guide 20 as the yarn from the removed finger, 13, occupied.

In accordance with the invention, the yarns in action, e. g. 10 and 11, approach the needle bank or banks in a more or less side by side relation and in a plane substantially perpendicular to the needle staffs 24 (e. g. in a horizontal plane when the needles are vertical as shown at A in Figs. 1 and 2), and of course first come to a needle the latch of which is open, and in about the relation to the latch shown at A in Fig. 1. As the yarn guides (including the plate guide 20, if used) continue to move away from the needle, and the needle is retracted toward cast-off position (or its retraction toward this position is continued, if started previously), the closing of the needle latch 25 first causes the latch to engage the outermost yarn 10 (position B, Figs. 1 and 2) and then thrust this outermost yarn to a position between the inner yarn 11 and the needle hook (position C). As a result, when the needle hook is drawn to or within the edge of the needle bed 27 (or forecuts at the edge of the bed, Fig. 4) so that a new loop is formed and casting-off of the old or previous loop 10a—11a occurs (about position D), the initially-outermost yarn 10 is necessarily outermost within the needle hook. As the needle is projected again, the two yarns 10 and 11 continue to occupy the same positions relative to each other (position E, Figs. 1 and 2). Accordingly the two yarns, e. g. 10 and 11, are plated one on the other in a uniform manner. In any stitch, the outermost yarn 10 will be exposed to the eye at the side of the fabric which contains the loop or closed end of the stitch, and the innermost yarn 11 will be exposed to the eye at the opposite side of the fabric. Obviously the needles can be projected and retracted by any desired sort of mechanism, pattern controlled or otherwise; for example by a cam system as suggested in Fig. 5.

The foregoing description has had reference particularly to cases where all the yarn loops are drawn to one and the same side of the fabric of course, at least for a portion of a fabric. In such cases, one side or face of the fabric (or portion of the fabric) will appear to the eye to be composed of the yarn 10 and the other side or face to be composed of the other yarn 11, except as there may be some slight departure from this due to variation in the needle operations, e. g. by the use of welt or tuck stitches. On the other hand, where some stitches of a fabric are drawn to one side of the fabric and the remainder are drawn to the other side, e. g. in the manner of a links-and-links machine, a different action occurs. Thus, Fig. 3, when a links-and-links needle 30 draws a loop of, say, two yarns 10 and 11 in one direction (say upwardly) the outermost yarn 10 passes to one side (say below) the innermost yarn 11, but if this needle draws a loop of the same yarns in the opposite direction (say downwardly) then the outermost yarn 10 passes to the opposite side (say above) the innermost

yarn 11. Accordingly at any loop stitch of a fabric made by such operations, one of the yarns, say 10, will lie at one side or face of the fabric if the stitch is drawn in one direction, but will lie at the opposite side or face of the fabric if the stitch or loop is drawn in the opposite direction. Hence fancy effects in color or yarn texture can be obtained at either side of the fabric by merely varying the directions in which the various stitches are drawn. That the direction in which the knit stitches are drawn in links-and-links machines is readily varied is well understood, and is indicated in Figs. 4 and 5. Fig. 4 shows one known manner of actuating by cams the jacks 31 which in turn actuate the needles 30, and in Fig. 5 is briefly outlined a known system of cams for actuating, at one feed, links-and-links double-ended needles 30 by jacks, and transferring the needles at will from a lower needle cylinder 32 to an upper cylinder 33 and vice versa. In the cam system of Fig. 5 the stitch cams will be recognized at 34. In view of the present knowledge of links-and-links knitting machines, the foregoing need not be described further at present.

It will be understood that my invention is not limited to the details of construction and operation shown in the drawing and described above, except as appears hereafter in the claims, and that the claims are intended to include equivalents of the elements mentioned in them.

I claim:

1. The method of feeding yarns to a bank of needles to form a knitted plated fabric, which consists of feeding at least two yarns to the needles simultaneously, substantially side by side in substantially the same horizontal plane which is at right angles to the needle staffs, said yarns being fed to the needle bank in a position where the closing needle latches engage one of said yarns and thrust it to one side or the other of the other of the said yarns.

2. The subject matter of claim 1, characterized by the fact that some of said needles draw loops upwardly and their latches engage the outermost yarn and thrust it below the innermost yarn, and other of said needles draw loops downwardly and the latches of the latter needles engage the outermost yarn and thrust it above the innermost yarn.

3. The method of forming a fancy knitted fabric which consists in feeding simultaneously at least two yarns to a bank of knitting needles, said yarns being fed substantially side by side in a plane substantially at right angles to the needle staffs and in a position where the closing needle latches engage one of said yarns and thrust it to one side or the other of the other of said yarns, and during at least a part of the time actuating at least some of said needles to draw loops of the yarns to one side of the fabric being knitted and actuating some of the needles to draw loops of the yarns to the opposite side of the fabric being knitted.

4. A knitting machine having a bank of needles, and a plating guide mounted in a fixed position with respect to the position of said bank of needles but movable with respect to the bank to feed yarn thereto, said plating guide having at least one guiding surface for yarn fed to the needle bank and disposed to direct a plurality of yarns to the needle bank simultaneously and substantially side by side in the same horizontal plane which is at right angles to the staffs of the needles.

5. The subject matter of claim 4, character-

ized by the fact that said plating guide has a plurality of yarn-guiding surfaces for simultaneous use.

6. The subject matter of claim 5, in combination with a yarn changer disposed to deliver yarns to said yarn-guiding surfaces.

CHARLES F. MILLER.
